UNITED STATES PATENT OFFICE

GEORGE L. GERLACH, OF HARRISON, NEBRASKA

SNOWPLOW

Application filed July 6, 1931. Serial No. 549,006.

This invention aims to provide a simple but effective means for removing snow from a road, railroad track or other place, and to provide novel means whereby a snow removing instrumentality may be operated from a tractor or other vehicle.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows in front elevation, a device constructed in accordance with the invention;

Figure 2 is a top plan, parts being broken away;

Figure 3 is a side elevation showing the device mounted on the tractor;

Figure 4 is a transverse section on the line 30 4—4 of Figure 2;

Figure 5 is a plan of the conveyor chain.

In carrying out the invention there is provided a support, which is denoted generally by the numeral 1. The support 1 may embody a vertical back plate 2, provided, intermediate its top and bottom, with a forwardly projecting shelf 3 which inclines downwardly and inwardly, from the opposite sides of the machine, toward the longitudinal median plane, as Figure 1 will clearly show. The numeral 4 marks a downwardly and forwardly inclined scoop which is connected to the forward edge of the shelf 3, as shown in Figure 4. The scoop 4 has vertical side walls 5 which extend backwardly

to the outer ends of the shelf 3. In order to facilitate the passage of the scoop over the ground, it is provided with shoes 6, although any equivalent for the specific shoes shown, may be supplied.

Inverted, L-shaped bearings 7 project forwardly and downwardly from the back plate 2 and are located near to the sides of the machine, as shown in Figure 1. In the back plate 2 and in the bearings 7, shafts 8 and 10 are journaled for rotation. The shafts 8 and 10 are placed near to the upper, outer ends of the shelf 3. A shaft 9 is journaled in the back plate 2 and is located at the central, lowermost portion of the shelf 3. The shafts 8, 9 and 10 are horizontally disposed and extend parallel to the direction of travel of the machine. Sprocket wheels 12 are mounted on the shafts 8, 9 and 10. About the sprocket wheels 12 is trained a sprocket chain 14, the constituent plate-like links of which have openings 15, for the reception of the teeth of the sprocket wheels 12. The links of the sprocket chain 14 have outwardly projecting blades 16, adapted to sweep along the shelf 3.

Any desired means may be provided for mounting the snow plow on a vehicle of any preferred type, and motion may be transmitted to the sprocket chain 14 in any preferred way. As shown, but not of necessity, the support 1 is secured on top of a bracket 17 having rearwardly extended arms 27, which are pivotally mounted at 18 on the axle of a tractor 19, the construction being such that the snow cleaning machine can have a vertical movement, thereby enabling the scoop 4 to work on the ground.

As to the driving mechanism, the shaft 8 may be a tubular shaft, as shown in Figure 4, and into this shaft is telescoped, for longitudinal movement, a squared shaft 20, the construction being such that when the shaft 20 is rotated, the shaft 8 will be rotated also.

By means of a universal joint 21 the rear

end of the shaft 20 is connected to a shaft 22, extended backwardly along the tractor 19. The rear end of the shaft 22 is connected by a universal joint 23 with a short shaft 24, which is horizontally disposed, the shaft 24 being journaled for rotation in a bearing 25, on the tractor 19. Through the instrumentality of bevelled pinions 26, the shaft 24 is connected with a vertical shaft 28, journaled 10 in the bearing 25. Bevelled gears 29 are shown as connecting the lower end of the shaft 28 with the power shaft 30 of the tractor 19. A reverse gear 31 is interposed in the shaft 28 and is provided with suitable 15 means 32, accessible from the driver's seat of the tractor 19, whereby the driver can reverse the rotation of the shaft 28, and parts connected with it at will.

In practical operation, the machine is advanced over the ground by the tractor 19, or 20 in any other suitable way. The snow is forced upwardly and backwardly, along the scoop 4, between the sides 5 of the scoop, and the snow is carried on the V-shaped shelf 3, underneath the sprocket chain 14. When 25 the sprocket chain is put into operation, the snow is raked by the blades 16 on the sprocket chain 14, upwardly along the shelf 3, and out at one side of the vehicle. The operator 30 can cause the snow to be raked out of the machine, at either side, as he may prefer, by a proper manipulation of the reverse gear 31. The sprocket chain 14 and the blades 16 not 35 only serve as a conveyor for the snow, but the snow, as well, is thoroughly broken up, and is put in such condition that it can be scraped out of the machine, at either side, by the action of the blades 16 on the sprocket chain 14.

40 It has been pointed out hereinbefore that it is desirable to have the snow removing mechanism capable of vertical movement, so as to conform to the surface of the ground. The mounting at 18 affords this. Owing to 45 the fact that a telescopic joint at 20-8 is provided in the driving shaft, and because the universal joints 21 and 23 are supplied, the machine will continue to work properly, notwithstanding any up and down movement 50 that the snow removing means may have, as it follows the surface of the roadway.

The drives are simple. Motion is derived 55 from the power driven shaft 30 of the tractor 19. The bevelled gears 29 transmit motion to the shaft 28, and from the shaft 28, motion is transmitted to the shaft 24 by the bevelled gears 26. The universal joint 23 transmits motion to the shaft 22, and the shaft 20 is rotated through the universal joint 21. The shaft 20, being of rectangular cross section, imparts rotation to the shaft 8, which, together with the corresponding sprocket wheel 12, operates the sprocket chain 14.

65 The device is simple in construction, but

it will be found to be thoroughly efficient in removing snow, as and for the purpose specified. The machine does not require much power to drive it, and it will remain in good condition without expert attention. The 70 machine can be attached to a tractor or other vehicle of standard construction, without working any objectionable changes therein.

Having thus described the invention, what 75 is claimed is:—

1. In a snow plow, the combination with a vehicle having a front axle, and ground wheels journaled on said axle, of a bracket and means for mounting the bracket on said axle for vertical swinging movement in a direction parallel to the line of advance of the vehicle, a substantially vertical back plate disposed transversely of the vehicle and carried by the bracket, a V-shaped shelf projecting forwardly from the back plate and mounted on the bracket, a downwardly and forwardly inclined scoop at the forward edge of the shelf and mounted on the bracket, a ground-engaging shoe at the forward end of the scoop and supporting the scoop for vertical swinging movement on the said axle, sprocket wheels supported for rotation on the back plate, two of the sprocket wheels being located adjacent to the outer ends of the shelf and symmetrically with respect to a vertical plane passing through the lowermost portion of the shelf, a third of the sprocket wheels being located directly above said lowermost portion of the shelf, a belt conveyor engaged around the sprocket wheels 80 and having elements movable along the shelf, to remove snow therefrom, and mechanism for operating one of the sprocket wheels.

2. In a snow plow, the combination with a vehicle having a front axle, ground wheels journaled on said axle, and a transverse, power-driven shaft on the lower, rear portion of the vehicle, of a bracket and means for mounting the bracket on said axle for vertical swinging movement in a direction parallel to the line of advance of the vehicle, a substantially vertical back plate disposed transversely of the vehicle and mounted on the bracket, a V-shaped shelf projecting forwardly from the back plate and mounted on the bracket, a downwardly and forwardly inclined scoop at the forward edge of the shelf, a ground-engaging shoe at the forward end of the scoop and supporting the scoop for vertical swinging movement on said axle, sprocket wheels supported for rotation on the back plate, two of the sprocket wheels being located adjacent to the outer ends of the shelf and symmetrically with respect to a vertical plane passing through the lowermost portion of the shelf, a third of the sprocket wheels being located directly above said lowermost portion of the shelf, a belt conveyor engaged around the sprocket wheels 90 and having elements movable along the shelf, to remove snow therefrom, and mechanism for operating one of the sprocket wheels.

snow therefrom, a backwardly-extended driven shaft journaled in the back plate and carrying one of said two sprocket wheels the driven shaft therefore being located far enough from the said vertical plane so that the driven shaft can extend backwardly along one side of the vehicle, means for supporting the rear portion of the driven shaft for rotation on the vehicle, and downwardly extended gearing connecting the rear end of the driven shaft with the said driven shaft of the vehicle.

In testimony that I claim the foregoing as my own, I have hereto affixed my signature.

GEORGE L. GERLACH.
